Attest,

United States Patent Office.

CHARLES H. WIGHT, OF BALTIMORE, MARYLAND.

Letters Patent No. 101,953, dated April 12, 1870; antedated February 15, 1870.

IMPROVEMENT IN INKSTANDS.

The Schedule referred to in these Letters Patent and making part of the same.

To all whom it may concern:

Be it known that I, CHARLES H. WIGHT, of Baltimore, in the county of Baltimore and State of Maryland, have invented certain new and useful Improvements in Inkstands; and I do hereby declare that the following is a full, clear, and exact description thereof, reference being had to the accompanying drawings and to the letters of reference marked thereon, which form a part of this specification, in which—

Figure 1 is a vertical section of my improved inkstand;

Figure 2 is a plan of case and passage; and

Figures 3 and 4 are perspective views of the passage and case on a reduced scale.

The nature of my invention consists in the construction of a fountain or reservoir for ink, in such a manner that the volume or main body of the ink will be held separately or disconnected from the ink in use, and admitting the same, when necessary, by means of a device that will be hereinafter described, into a well or reservoir, so made that only a limited quantity can be admitted from the fountain; and that the ink thus delivered from the fountain does not return to the same to vitiate the main body of the ink, but remains separate therefrom until consumed.

In order to enable others skilled in the art to which my invention appertains to make and use the same, I will now proceed to describe its construction and operation, referring to the annexed drawings, which show a longitudinal vertical section of my inkstand.

A represents the base, made of wood, metal, or other suitable material, upon which is secured a case or frame, B.

In the rear portion of the case B is an aperture, in which is inserted a collar, a, projecting downward from the bottom of a fountain or reservoir, C.

This fountain may be made of glass or other suitable material, and around its collar a is a plate, b, which is secured to the case B by means of dowel-pin e and set-screw d, or other mechanical devices answering the same purpose, thus firmly securing the fountain to the case and bed.

A cap, D, is fastened permanently on top of the fountain C by cement or other material.

Through the bottom of the fountain C is an opening, which is stopped from underneath by a valve-stopper, f, having a plunger, E, extending upward through the center of the fountain and the cap D, and its upper end provided with a detachable screw-head, G.

Between the screw-head G and cap D, around the plunger, is a spiral spring, h, which holds the plunger up, closing the valve.

In the cap D is also a vent, covered with a lid, g, for filling the fountain without removing the cap.

The plunger E and valve f may be of glass, hard rubber, or other suitable material. If of glass, the valve should be tipped with rubber.

When the screw-head G is pressed down the valve is opened, and the ink flows through the passage H into the well or reservoir I, at the front end of the case B.

In the well I is to be inserted a movable mouth-piece, for convenience in cleaning.

At the side thereof is a double-acting spring cover, J, constructed in the following manner:

At a suitable point in the case B is a small upright tube, k, through which is passed a rod, m, having a collar, n, at its lower end, within the case, and a collar, o, above the tube, said collar resting on the same.

Above the collar o the rod m is curved, and the cover J attached to its outer end.

Between the collar n and the under side of the case B, around the rod m, is a spiral spring, i, which holds the rod down.

The mouth-piece above mentioned being inserted in the well I, the cover J is raised up and turned directly over the same, when the spring i forces it down tight on the mouth-piece. In like manner it can be taken off and turned to one side when the inkstand is in use.

The quantity of ink admitted from the fountain C to the well I being small, is consumed before deterioration occurs; that remaining in the reservoir, being protected against the admission of dirt and evaporation, remains limpid.

Having thus fully described my invention,

What I claim as new, and desire to secure by Letters Patent, is—

1. The passage H, constructed substantially as described, in combination with case B, fountain C, and movable mouth-piece.

2. The plunger E, provided with spring h and valve f, seated from below, arranged in combination with fountain C, substantially as and for the purpose set forth.

3. The double-acting cover J, operated by means of the rod m, collars n o, spring i, and tube k, on the case B, substantially in the manner and for the purposes herein set forth.

In testimony that I claim the foregoing as my own, I affix my signature in presence of two witnesses.

CHARLES H. WIGHT.
